(57) **CLAIM**

The ornamental design for a tablet PC, as shown and described.

DESCRIPTION

FIG. 1 is a front perspective view of a tablet PC, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a tablet PC of FIG. 1, in which the tablet PC is in an open position;

FIG. 9 is another perspective view of a tablet PC of FIG. 1, in which the tablet PC is in an open position supported by a tablet stand of the tablet PC; and,

FIG. 10 is a left-side view of the tablet PC of FIG. 9.

The broken lines shown illustrate portions of the tablet PC that form no part of the claimed design.

The shade lines in the figures show contour and not surface ornamentation. The diagonal lines in the FIGS. 1, 2, and 8 represent a reflective surface.
